INVENTOR

BY *Victor J. Evans*

ATTORNEY

D. D. Leidy Jr.

WITNESS:

UNITED STATES PATENT OFFICE.

DANIEL D. LEIDY, OF BOYERTOWN, PENNSYLVANIA.

CATCH.

Application filed January 14, 1924. Serial No. 686,152.

To all whom it may concern:

Be it known that I, DANIEL D. LEIDY, a citizen of the United States, residing at Boyertown, in the county of Berks and State of Pennsylvania, have invented new and useful Improvements in Catches, of which the following is a specification.

This invention relates to catches or fasteners for burial caskets, and an object of the invention is to provide a catch or fastener which is comparatively simple in construction, easily operated, and which will prevent relative movement of the cover and body of a casket, preventing longitudinal and lateral movement of the cover relative to the body, as well as preventing upward or lifting movement of the cover.

A further object of this invention is to provide a catch or fastener as specified, which may be readily released to permit removal of the cover of the casket when desired, and one which may be manufactured at a low cost and will not detract from the appearance of the casket.

Other objects of the invention will appear in the following detail description, and in the accompanying drawings wherein:

Figure 1—is a section through a fragment of a casket and cover showing the improved catch or fastener in place.

Figure 2—is a perspective view of the catch.

Figure 3—is a top plan of the receiving section of the catch.

Figure 4—is a longitudinal section through the receiving portion of the catch.

Figure 5—is a detail section taken on the line 5—5 of Figure 1.

Referring more particularly to the drawings, the improved catch or fastener comprises a plate 1 which is attached by means of screws or analogous fastening devices to the cover of the casket and has a transversely extending hook 2 formed on one edge thereof, of which is adapted to engage through the rectangular slot 3 in the keeper plate 4. The keeper plate 4 is carried by the side of the casket and the side wall of the casket is grooved or cut-away to receive the hook 2. The keeper plate 4 is provided with a tapered concave lead 5 leading to one end of the slot 3 which serves as a guide for guiding the movement of the hook 2 through the opening 3. The opening or slot 3 has its end 6 reduced in width, and the body 7 of

the hook 2 is adapted to engage beneath the keeper plate 4 beyond the limit of the reduced end 6, while the connecting portion 8 of the hook engages in the reduced portion to prevent relative lateral movement of the hook 2 and consequently of the casket cover relative to the casket body.

The casket cover is recessed so that the plate 1 will lie flush with the undersurface of the cover and it is further recessed to permit the depression thereinto of the locking plate 9. The locking plate 9 is preferably formed of spring steel and it is attached at one end to the casket cover by means of the same screws which serve to attach the plate 1 to the cover. The locking plate 9 has a locking cam 10 formed integrally therewith and extending transversely therefrom at one end and at its free end. The cam 10 has an arcuate surface 11 which is adapted to ride over the lead 5 and the keeper plate 4 during the connecting movement of the cover and body of the casket after which the cam engages in the slot in the keeper plate and prevents lateral movement of the cover and body of the casket. The spring locking plate 9 has a thumb button 12 formed integrally thereon which projects laterally from the lower end of a connecting tongue 13. The connecting thumb 13 is positioned at the opposite side of the locking plate 9 from the cam 10 and by upward pressure on the button 12, the cam 10 may be forced into the recess 14 in the cover to permit disconnection of the cover and body.

While in the drawings and in the foregoing description the improved catch or fastener has been shown and described for use in connection with burial caskets, it is to be understood that it may be used in connection with any type of box or closure without departing from the spirit of this invention.

It is, of course, to be understood, that the invention may be constructed in various other manners and the parts associated in different relations, and therefore, I do not desire to be limited in any manner, except as set forth in the claim hereunto appended.

What I claim is:

A device of the class described comprising a plate having a hook formed at one edge thereof and extending transversely to the plate, a spring plate lying in abutment

2
with one side of the first named plate, a cam projecting transversely from one edge of the spring plate and having a rounded edge facing said hook, and a thumb button 5 formed upon said spring plate for moving the cam out of locking position relative to said hook, a keeper plate provided with a

longitudinal slot adapted to receive said hook and cam, one end of the slot in said keeper plate being reduced in width to substantially 10 the thickness of said hook.

In testimony whereof I affix my signature.

DANIEL D. LEIDY.
